UNITED STATES PATENT OFFICE.

JAMES YUILL, OF TORONTO, ONTARIO, CANADA, ASSIGNOR OF ONE-THIRD TO WILLIAM HOMEWOOD TAYLOR STEVENS, OF TORONTO, ONTARIO, CANADA, AND ONE-THIRD TO LEONARD RAHNE, OF FORT GEORGE, BRITISH COLUMBIA, CANADA.

SNAP ELECTRIC-LIGHT SWITCH.

1,143,876.

Specification of Letters Patent. Patented June 22, 1915.

Application filed June 19, 1914. Serial No. 846,121.

To all whom it may concern:

Be it known that I, JAMES YUILL, a subject of the King of Great Britain, residing at Toronto, in the county of York, in the 5 Province of Ontario, Dominion of Canada, have invented new and useful Improvements in Snap Electric-Light Switches, of which the following is a specification.

My invention relates to a snap electric 10 light switch and has as its principal object the provision of a switch which will interrupt the circuit in which it is connected only after an appreciable interval after receiving an operative impulse.

15 A second object of my invention is to provide a switch of the character described in which the time lag of the switch after receiving the operative impulse may be adjusted.

20 A final object of my invention resides in the particular arrangement and combination of parts hereinafter described.

Referring more particularly to the drawing, Figure 1 is a plan view of my device, 25 partly broken away, the outer casing being removed. Fig. 2 is a central sectional view through the device shown in Fig. 1 the casing being in place. Fig. 3 is a detail view of the means for regulating the time lag. 30 Fig. 4 is an inverted view in perspective of certain of the parts shown in Fig. 1. Fig. 5 is a perspective view of the retarding piston and a portion of its rod. Fig. 6 is a perspective view of the outer casing and 35 snap member. Fig. 7 is a central sectional view of the packing ring used with the piston, the body of the piston being shown in outline only.

In the separate views the same part is 40 designated by the same reference character.

Referring more particularly to the drawing, I is a base plate of insulating material which may be suitably fastened to a wall or other support. Mounted centrally of the 45 base plate I is a spindle 11 on which is rotatably mounted a sleeve which carries a connecting bar or arm 7 which extends on each side of the spindle 11, the ends of 50 which are arranged to contact either with the pole segments 8-8 or with the insulation blocks 9-9. A spring 12 is connected to the bar 7 and to the cover 13 in such a

manner as to normally urge the bar 7 toward the blocks 9-9, or in other words, toward the off position. A handle 10 is also 55 provided for moving the connecting arm in either direction, the handle being connected to the arm by means of a sleeve as shown.

Operatively connected to the arms 7-7 are two curved rods 4-4 which carry pistons 3 such as are illustrated in Figs. 5 and 7. The pistons 3 are arranged to work back and forth in annular cylinders such as 2-2, the central line of the cylinders 2 being concentric with the spindle 11. One 60 end of each cylinder is open as indicated in Fig. 1 while the opposite end is closed by a head such as 5 and each piston carries a packing ring or cup leather such as 16 which is so arranged, as shown, as to force the air 65 toward the head 5 when the piston is moved in that direction, but which will allow air to pass into the cylinder readily when the piston is moved in the opposite direction. It will be seen that the movement of the 70 pistons toward their corresponding heads takes place when the arms 7 are turned toward the off position, and that the springs 12 also urge the arms in the direction just mentioned. It will be understood, however, 75 that the pole segments 8-8 are provided with raised sections or projections on which the bars 7 are shown in Figs. 1 and 4. The friction between these raised projections and the ends of the bars is sufficient to resist the 80 tension of the spring and hold the switch in the on position so long as desired. However, if the handle 10 is turned sufficiently 85 so that the arms 7 are moved off the raised portion, the arms are still in sufficient contact with the pole segments to maintain the circuit through the switch but the spring 12 continues the motion of the arms 7 toward the off position, the rapidity of such motion being determined by the pistons 3. 90

In order to permit the air to escape from the cylinders 2 and permit the spring to turn the arms further, the heads 5 are apertured as clearly shown in Figs. 1 and 3, and an adjustable screw 6 is mounted in each head so that the rapidity of the escape of the air from the cylinders in front of the pistons 3 can be regulated as desired. In 100 practice these screws can be adjusted so that

the time required for the connecting arms to move from the on to the off position may vary from one second to several minutes.

It will be obvious that when the bars 7 5 are turned from the insulating segments 9 to the on position that there will be little or no resistance offered by the pistons 3 because the air can pass by the cup leathers 16.

It will be seen that by the use of my invention a switch controlling the lights in a room may be given an impulse and then the person who initiated the movement of the switch will still have time to leave the room while the lights are burning. It will be 15 understood, moreover, that while I have shown and described the preferred form of my invention, I do not wish to be limited thereto except for such limitations as the claims clearly import.

20 Having thus described my invention, what I claim is:

1. An electric switch comprising in combination, a member for closing the circuit, frictional means for holding said member in 25 position to close the circuit, and means for moving said member into position to open the circuit after the beginning of the opening movement.

2. An electric switch comprising in combination, a member for closing the circuit, frictional means for holding said member in position to close the circuit, and spring means for moving said member into position to open the circuit after the beginning of 35 the opening movement.

3. An electric switch comprising in combination, a member for closing the circuit, frictional means for holding said member in position to close the circuit, spring means 40 for moving said member into position to open the circuit after the beginning of the opening movement, and means for retarding the operation of said spring means.

4. An electric switch comprising in combination, a member for closing the circuit, frictional means for holding said member in position to close the circuit, spring means for moving said member into position to open the circuit after the beginning of 50 the opening movement, and adjustable means for retarding the operation of said spring means.

5. A switch comprising in combination, at least one pivotally mounted arm, spring 55 means normally tending to throw said arm to the off position, friction means for hold-

ing said arm in the open position, and a dash pot for opposing the force of said spring during the opening movement.

6. A switch comprising in combination, a 60 casing and base plate of insulating material, a spindle therefor, a revoluble sleeve carried thereon, and having two circuit closing arms which extend in opposite directions, spring means located on said sleeve concentric 65 thereto and arranged to move said arms to the off position, a segmental arm attached to one of said arms, a dash pot member connected to said segmental arm to oppose the force of said spring during the opening 70 movement, and frictional means whereby said first mentioned arms are held in position to close the circuit when desired, substantially as described.

7. A switch comprising in combination, a 75 casing and base of insulation, a spindle therefor, a revoluble sleeve carried thereon having two arms which extend in opposite directions, spring means located on said sleeve concentric thereto and arranged to 80 move said arms to the off position, a segmental arm attached to one of said arms carrying at the end a piston having a cup leather, an annular cylinder in which said piston works having located at its head a 85 screw for regulating the flow of air therethrough, and contact blocks for coöperating with said arms to close the circuit, said blocks having raised portions for frictionally engaging said arms for holding the 90 arms in position to close the circuit.

8. An electric switch comprising in combination, a member for closing the circuit, arrangements for holding said member in position to close the circuit, a spring for 95 moving said member into position to open said circuit after the beginning of the opening movement, and a dash pot for retarding the opening movement of said member, said arrangements comprising contact blocks coöperating with said member for closing the circuit, said blocks having each a raised portion thereon affording frictional means for holding said member in the position to close the circuit. 100 105

In testimony whereof I affix my signature in the presence of two witnesses.

JAMES YUILL.
